UNITED STATES PATENT OFFICE.

WILLIAM CARRY, OF NEWPORT, RHODE ISLAND, ASSIGNOR OF ONE-HALF
TO WILLIAM SHEPLEY, OF SAME PLACE.

DESIGN FOR A PARCEL-CARRIER.

SPECIFICATION forming part of Design No. 35,096, dated September 17, 1901.

Application filed June 29, 1901. Serial No. 66,617. Term of patent 7 years.

To all whom it may concern:

Be it known that I, WILLIAM CARRY, a citizen of the United States, and a resident of Newport, in the county of Newport and State 5 of Rhode Island, have invented and produced a new and original Design for Parcel-Carriers, of which the following is a full, clear, and exact description.

Reference is to be had to the accompanying drawing, forming a part of this specification, in which the figure is a perspective view of a parcel-carrier, showing my design.

The design consists of the hooks A A', the straight alined bars B B', from the outer ends 15 of which the hooks depend, the outer members of the hooks extending up substantially parallel with the inner members and terminating at a point about on a level with the

said bars, the twist C at the inner end of the bars and standing at right angles thereto and 20 in the same vertical plane with the hooks, but at the opposite side of the said bars, and the ring D at the outer end of the twist and also in the same vertical plane with the hooks.

Having thus described my invention, I 25 claim as new and desire to secure by Letters Patent—

The design for a parcel-carrier herein shown and described.

In testimony whereof I have signed my 30 name to this specification in the presence of two subscribing witnesses.

WILLIAM CARRY.

Witnesses:

WILLIAM O. MILNE,
J. STACY BROWN.
